UNITED STATES PATENT OFFICE.

DANIEL J. BUTTERFIELD, OF LOS ANGELES, CALIFORNIA.

CHECK-CONTROLLED APPARATUS.

Application filed February 4, 1922. Serial No. 534,062.

To all whom it may concern:

Be it known that I, DANIEL J. BUTTERFIELD, a citizen of the United States, residing at Los Angeles, in the county of Los Angeles and State of California, have invented certain new and useful Improvements in Check-Controlled Apparatus, of which the following is a specification, reference being had therein to the accompanying drawings.

This invention relates to a check-controlled apparatus, and the object of the invention is the construction of an efficient and durable machine, the operation of which is controlled by the insertion of a coin, which machine will dispense liquid into a receptacle upon the placing of a coin in the machine.

This application is a continuation in part of my original application, Serial No. 421,393, which has matured into Patent No. 1,407,838.

With the foregoing and other objects in view, my invention comprises certain novel combinations, constructions and arrangements of parts as will be hereinafter described, illustrated in the accompanying drawings, and more particularly pointed out in the appended claim.

In the drawings:

Figure 1 is a vertical, sectional view, taken on line 1—1, Fig. 2, and looking in the direction of the arrows.

Figure 2 is a vertical, sectional view, taken on line 2—2, Fig. 1, and looking in the direction of the arrows.

Referring to the drawings by numerals, 1 designates the casing which includes the front section 2, the central section 3, and the rear section 4. In the front section 2 is formed an upper coin slot 5, at the bottom of which is a compartment 6, that communicates with the lower coin slot 7; the lower coin slot 7 opens into the compartment or receptacle 8. Adjacent to the upper coin slot 5 is a compartment 9, Fig. 1, in which compartment is mounted lever 10. Lever 10 is pivotally supported at 11, within compartment 9. Lever 10 has a coil spring 12 bearing against the same for holding the lever out in the path of movement of a coin 13, Fig. 1. When the coin 13 is placed in slot 5, the weight of the coin is sufficient to overcome the outward pressure of spring 12, resulting in the lever 10 being pushed inwardly as the coin travels to its

lowest position within the upper coin slot and into the compartment 6. The lower end of lever 10 is enlarged, at 14, and on one side of this enlarged portion 14 are a pair of pins 15. The cog 16 is rotatably mounted in the compartment 9 and the teeth of the cog 16 engage the pins 15, of lever 10; also, said teeth engage cups or receptacles 17 in the compartment 18. One tooth of each cog 16 only engages a cup 17, and when the lever 10 is pushed inwardly by the coin 13, the tooth that is engaging a cup will slightly raise the cup until the tooth passes the edge of the cup and then the cup will drop down and out of the compartment 18 and the next cup will fall against a tooth of the cog 16 and will not be discharged until another coin has been dropped into the slot 5. The lower pin on the lever 10 operates or rotates the cog, while the upper pin acts as a stop or brake for limiting rotary movement of the cog each time the coin 13 is dropped in the slot 5.

A primary valve 19 is positioned in the central section 3 of casing 1, and an auxiliary valve 20 is positioned in the rear section 4. The primary valve 19 is operated by a coin-controlled pusher device; this coin-controlled pusher device comprises a manually-operated outer section 21 and an inner section 22. The outer section 21 includes the push cap 23, pin 24^a and spring 25.

A stem 27 is provided for the valve 19 and is provided at its outer end with a head 26. A spring 28 is provided about this stem 27 and normally holds the stem in the position shown in Figure 2 with the valve 19 in the closing position against the seat 29 and the cross slot 26^a of the head 26 registering with the coin chute 5. It will therefore be seen that when a coin is placed in the chute and rests upon the abutment 5^a, this coin will extend into the slot 26^a and engage the strip 26^b. The strip 26^b will therefore be moved upon the pivot pin at its upper end against the action of the spring 26^c and will extend across the pocket 30 so that when the cap 23 is moved inwardly the pin 24^a will engage the strip and move the stem 27 inwardly to move the valve 19 to an open position. When the stem 27 and head 26 are moved inwardly the coin will be moved off of the abutment and will drop into the coin box

but the strip 26^b will not return to its normal position until pressure upon the cap 23 is removed.

The auxiliary valve device 24 is operated by liquid pressure, the inner end of pin 27 engaging the same; this valve device 24 comprises shaft or pin 31, provided with valve 20, and on the inner end of pin 31 is a plunger head or "cap" 32 against which the inner end of pin 27 engages. When the valve device 24 is moved toward the outer end of section 4, the valve 20 will be unseated, permitting water or carbonated water to enter the rear end 33 of the casing 1, passing from section 4 into by-pass 34 (dotted lines, but more fully disclosed in my original application, Serial No. 421,393) and discharges into nozzle 35.

The syrup receptacle 36, preferably formed of transparent material, such as glass, is mounted upon the casing 1 and communicates with the interior thereof. The valve device 37 is mounted upon the receptacle 36 for permitting air to pass from within the receptacle as syrup or liquid fills the same. Syrup is supplied to the receptacle 1 by supply pipe 38.

It is to be understood that the spring 28, as well as spring 38 normally retains the valves 19 and 20 in a closed or seated position for preventing liquid passing through the casing until a coin has been dropped in the machine; upon a coin being dropped in the machine, the manually-operated pusher device 21 can be forced inwardly to move the primary valve 19 to an open position (see dotted lines, Fig. 2), and when the device is in the position shown by dotted lines, it will close the inner end of supply pipe 38, preventing any more syrup being discharged into the section 3 and receptacle 36, while the syrup is being discharged from receptacle 36 through nozzle 35. The supply pipe 38 normally keeps the receptacle 36 filled.

The inward movement of valve 19, from

its seated position, will result in the inner end of pin 27 pushing against the plunger head or "cap" 32, forcing it inward, causing the auxiliary valve 20 to move to an open position, permitting water or carbonated water to pass through pipe 34 and be discharged at the same time the syrup is discharged through nozzle 35. On the extreme inner end of shaft or pin 27 is closure device 39, for pipe 38; the pipe 38 opens into section 3, and when the auxiliary valve 19 is moved to its innermost position, as shown by dotted lines (Fig. 2) syrup will momentarily be prevented from entering the casing 1 through pipe 38, but upon the return of valve 19 to its seated position, syrup can flow through pipe 38 and fill the receptacle 36.

Further reference may be had to the drawings and specification in my co-pending, original application, Serial No. 421,393.

What I claim is:

In a structure of the character described, a casing, a coin chute intersecting said casing, dispensing means including a spring pressed inner plunger having a head at its outer end provided with a transversely extending slot normally registering with the coin chute, the head having a pocket extending axially of the plunger, a strip movably mounted in the slot and adapted to be engaged by a coin placed in the chute and be moved to extend across the pocket, an outer actuating plunger spring held against inward movement and slidably into the pocket and adapted to impart movement to the inner plunger when a coin is positioned in the slot and the strip moved across the pocket and engaged by the inner end of the outer plunger.

In testimony whereof I hereunto affix my signature.

DANIEL J. BUTTERFIELD
